US00D425809S

United States Patent [19]

Zabawski et al.

[11] Patent Number: Des. 425,809

[45] Date of Patent: ** May 30, 2000

[54] **HOUSING FOR EMITTERS FOR INFRARED DETECTORS**

[75] Inventors: **Henrick A. Zabawski**, Arlington Heights; **Robert R. Kornowski**, Schaumburg; **Chong S. Kim**, Naperville; **Chris L. Tsakiridis**, Chicago; **Daniel R. Schroeder**, Carol Stream; **Matthew A. Stahl**, Des Plaines, all of Ill.

[73] Assignee: **Lumex, Inc.**, Palatine, Ill.

[**] Term: **14 Years**

[21] Appl. No.: **29/072,425**

[22] Filed: **Jun. 17, 1997**

[51] LOC (7) Cl. **10-05**

[52] U.S. Cl. **D10/106**

[57] CLAIM

The ornamental design of a housing for emitters for infrared detectors, as shown.

DESCRIPTION

FIG. 1 is a bottom perspective view of a housing emitters for infrared detectors, such as a light emitting diode, accoding to one preferred embodiment of this invention;

FIG. 2 is a front view of the housing for emitters for infrared detectors, as shown in FIG. 1 ;

FIG. 3 is a rear view of the housing for emitters for infrared detectors, as shown in FIG. 1 ;

FIG. 4 is a side view of the housing for emitters for infrared detectors, as shown in FIG. 1 ;

FIG. 5 is a side view, opposite the side view shown in FIG. 4, of the housing for emitters for infrared detectors, as shown in FIG. 1 ;

FIG. 6 is a top view of the housing for emitters for infrared detectors, as shown in FIG. 1; and,

FIG. 7 is a bottom view of the housing for emitters for infrared detectors, as shown in FIG. 1.
